(57) **CLAIM**

The ornamental design for a monitor, as shown and described.

DESCRIPTION

FIG. 1 is a perspective view of a monitor, showing my new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is a rear perspective view thereof;

FIG. 9 is a perspective view of the monitor of FIG. 1, in which the unclaimed display and stand portions of the monitor in broken line are removed to further show the remaining portion of claimed design;

FIG. 10 is a front view of the remaining portion of FIG. 9;

FIG. 11 is a rear view of the remaining portion of FIG. 9;

FIG. 12 is a left-side view of the remaining portion of FIG. 9;

FIG. 13 is a right-side view of the remaining portion of FIG. 9;

FIG. 14 is a top plan view of the remaining portion of FIG. 9;

FIG. 15 is a bottom plan view of the remaining portion of FIG. 9; and,

FIG. 16 is a rear perspective view of the remaining portion of FIG. 9.

The broken lines are for illustrative purposes only and form no part of the claimed design. The shade lines in the figures show contour and not surface ornamentation. The dot-dash lines define unclaimed boundaries of the claimed design and form no part of claimed design.
